UNITED STATES PATENT OFFICE.

ROBERT S. PHILLIPS AND BENJAMIN H. PHILLIPS, OF RIVERSIDE, NEW JERSEY.

STOCKING.

1,123,587.

Specification of Letters Patent.

Patented Jan. 5, 1915.

Application filed February 6, 1913. Serial No. 746,517.

To all whom it may concern:

Be it known that we, ROBERT S. PHILLIPS and BENJAMIN H. PHILLIPS, citizens of the United States, residing at Riverside, in the county of Burlington and State of New Jersey, have invented certain new and useful improvements in Stockings, of which the following is a specification.

Our invention relates to certain new and useful improvements in stockings and the like, and one object thereof is to so form the knee portion thereof that it will conform to the knee of the wearer.

A further object is to so form a stocking that the courses of stitches over the knee will not be stretched as are the stitches at the back, so that the stocking over the knee will not be put under excessive tension when the knee of the wearer is bent.

20 A further object is to so form the knee portion that the stocking may be readily knit on substantially any of the automatic knitting machines now used for knitting stockings and the like.

25 With the foregoing and other objects in view our invention consists in certain constructions, combinations and arrangements of parts, the preferred form of which will be first described in connection with the accompanying drawing and then the invention particularly pointed out in the appended claims.

30 Referring to the drawing wherein the same part is designated by the same reference numeral wherever it occurs: Figure 1 is a side view of a stocking constructed in accordance with our invention; Fig. 2 is an enlarged diagrammatic view showing how the additional courses are added to the knee portion of the stocking, and Fig. 3 is a section through the knee portion showing how the thread that forms the extra courses is carried from one extra course to the next.

35 5 designates the portion of a stocking above the knee portion, 6 the portion thereof below the knee, 7 the portion which extends over the knee, and 8 the portion at the back of the knee, and it is to be noted that preferably and as shown the portions 7 and 8 each extend about half way around the knee and join at the seams 9. It is to be understood however that the relation between the parts 7 and 8 and the location of the seams 9 can be varied as desired, provided that

and width to at least substantially cover the knee of the wearer, without departing from our invention.

In describing the manner of knitting our improved stocking we will assume that the stocking is commenced at the top and finished at the toe in the usual manner, though the particular manner in which it is knit is entirely immaterial to our invention. In knitting the stocking from the top, the knitting is begun and carried on in the usual manner and the part 5 is formed as in an ordinary stocking until a point is reached preferably just above the knee. When a course is knit running entirely around the stocking with the thread 10 with which the portion 5 has been knit and then an extra thread 11 is thrown in and a course knit across the portion 7 and when it reaches the end of this portion this thread is suppressed and floated across the inside of the stocking while the knitting is continued around with the thread 10 and when the seam 9 is again reached the extra thread 11 is again thrown in and the operation continued until a point below the knee is reached when the extra thread is cut off and the stocking furnished in the ordinary manner. Then the portions of the thread 11 which had been floated across are cut off as indicated at the marks 12 and the stocking is complete.

It will be observed that by our improvement there are twice as many courses of stitches in the portion 7 as there are in the portion 8, and that therefore when the stocking is taken at its ends and stretched taut the stitches in the portion 8 will be drawn out into long narrow loops without however drawing out the stitches in the portion 8, as illustrated in Fig. 2, so that when the stocking is worn the knee may be bent without putting undue tension on the knee portion.

While we have described the manufacture of our stocking by throwing in an extra thread, it is of course to be understood that the same may be knit with a single thread by properly running the courses and the same result produced as that just described.

We realize that considerable variation is possible in the details of construction and arrangement of parts without departing from the spirit of our invention, and we therefore do not intend to limit ourselves to the specific form shown and described.

Having thus described our invention what we claim as new and desire to secure by Letters Patent is:

A stocking formed by knitting the portions above and below the knee in the ordinary manner, the knee portion being formed by throwing in an extra thread over the front of the knee portion and then floating it across the interior of the stocking while 10 knitting a full course with the regular thread and then knitting another course

over the front portion with the extra thread, said regular thread and extra thread alternating with each other.

In testimony whereof we affix our signatures in presence of two witnesses.

ROBERT S. PHILLIPS.
BENJAMIN H. PHILLIPS.
